UNITED STATES PATENT OFFICE.

WALTER B. POLLARD, OF RIDGE SPRING, NORTH CAROLINA.

DESIGN FOR A HAME REPAIR-HOOK.

SPECIFICATION forming part of Design No. 27,075, dated May 18, 1897.

Application filed February 25, 1897. Serial No. 625,058. Term of patent 7 years.

To all whom it may concern:

Be it known that I, WALTER B. POLLARD, of Ridge Spring, in the county of Greene and State of North Carolina, have invented a new 5 Design for Hame Repair-Hooks; and I do hereby declare the following to be a full, clear, and exact description of the invention, such as will enable others skilled in the art to which it pertains to make and use it, reference being had to the accompanying drawings, which form part of this specification.

My invention relates to a design for hame repair-hooks, which is illustrated in the accompanying perspective view.

15 The design consists of a single piece of metal doubled at the point *a*, so that the bulged eye *b* is at one side of the hook. Each end has a hook formed of a vertical passage-

way *c* and a horizontal passage-way *d*, communicating therewith, the upper wall of the 20 horizontal passage-way being inclined upward and provided with an inwardly-extending rounded projection *e*, and the other ends of the hook are rounded.

Having thus described my design, what I 25 claim, and desire to secure by Letters Patent, is—

The design for a hame repair-hook, substantially as herein shown and described.

In testimony whereof I affix my signature 30 in presence of two witnesses.

WALTER B. POLLARD.
